HERBERT H. STEELE, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 909,473.

Specification of Letters Patent.

Patented Jan. 12, 1909.

Application filed July 11, 1906. Serial No. 325,563.

To all whom it may concern:

Be it known that I, HERBERT H. STEELE, citizen of the United States, and resident of Syracuse, in the county of Onondaga and 5 State of New York, have invented certain new and useful Improvements in Type-Writing Machines, of which the following is a specification.

This invention relates to improvements 10 in carriage-retarding apparatus for type-writing machines and it consists of the features of construction and combinations and arrangements of parts which will be herein-after described and specified in the claims.

15 In the accompanying drawings in which like reference numerals designate like parts in different views, Figure 1 is a rear and sectional elevation of the frame and parts of the mechanism of a Monarch typewriting machine to which the carriage-retarding apparatus embodying the invention is applied; Fig. 2 is a vertical section, on the plane indicated by the broken line near the left of Fig. 1, of said frame and parts of the mechanism 20 of the machine, the sectional plane being seen from the right side of the machine; Fig. 3 is a rear elevation on an enlarged scale of a lifting device which is less clearly shown in Fig. 1; Fig. 4 is a vertical section of the upper rear part of the machine, the section being at right angles to the axis of the platen, and the section-plane being seen from the left side of the machine; Fig. 5 is a rear and 25 sectional elevation of parts of the retarding apparatus and mechanism connected therewith; Fig. 6 is a top and partly sectional view of the mechanism shown in Fig. 5; Fig. 7 is a perspective of a bracket; and Fig. 8 is an end view of a rotary device which is 30 partly shown in Fig. 6, and of the body of a cylindrical case in which this device is confined.

Although the drawings illustrate the invention applied to a Monarch machine, it is 35 to be understood that it is also applicable to numerous other machines including such as are called "under-stroke" machines, as well as "visible-writing" machines.

The carriage-retarding apparatus in which 40 the invention is embodied is attached to the top plate of the machine near its rear edge and on the left, preferably, of a vertical plane containing the axis of the escapement pinion. The frame of the machine is composed

of a base 1 and four posts 2, only three of 55 which are shown, and the top plate 3. On the back part of the top plate are two standards 4, which are fastened to the top plate, and to which upper and lower guide rails 5 and 6 are attached by screws 7, these guide 60 rails having in them grooves 8 and 9 extending throughout the length of the rails. The carriage 10, in which is mounted a platen 11, has formed on it grooved guides 12 and 13 which extend from end to end of the carriage, the grooves 14 and 15 of these guides forming with the grooves 8 and 9 of the rails 5 and 6 ball or roller channels in which are shown anti-friction balls 16 and 17. The carriage is thus supported by the rails 5 and 6 and is movable on the balls in opposite directions over the top plate 3. The guides 12 and 13 are connected together by webs 18, and between these guides extend arms 19 which are pivoted to the ends of the carriage 75 and to whose rear ends are fixed the carriage rack 20, which is movable up and down on the pivots 21 of the arms 19. Springs 22, acting on the arms of the rack, tend to keep the rack in the position in which it is shown 80 in Fig. 1, that being its normal position.

The rack 20 normally engages a pinion 23, which is fast on a shaft having a bearing in a bracket 24 affixed to the top plate 3, and on the rear end of this shaft is an escapement-wheel 25, arranged to co-act with the feed dogs 26 and 27, which are mounted on a dog rocker 28 whose rock shaft 29 is pivoted at its ends between lugs on the bracket 30 affixed to and extending downward from the 90 top plate 3. On the rock shaft 29 is a spring 31 which tends to keep the stepping dog 27 in engagement with a tooth of the escapement-wheel 25. An arm 32, fast on the dog rocker, extends in front of the rock shaft 29, 95 and to the front end of this arm is secured a link 33 which extends downward therefrom to the universal bar of the machine. Whenever the universal bar is actuated by depressing a character-key or a space-key, the front 100 end of the arm 32 is drawn downward by the link 33, the stepping dog 27 is swung forward free from the escapement-wheel, and the holding dog 26 is moved into engagement with the escapement-wheel, and when the 105 universal bar rises after the key has been released, the stepping dog 27 reengages with the escapement wheel and the carriage ad-

vances a letter space distance. But if desired a reverse feed escapement may be used instead of that above described.

To the standards 4 are rigidly attached 5 rearwardly extending arms 34, in which a stop bar 35 is journaled at its ends. On the right end of this stop bar, outside of the adjacent arm 34, is a crank arm 36 which normally extends both forward and upward 10 from the stop bar, and to which is pivoted at its front end a rod or link 37, which extends downward to the crank arm through the top plate and into the base 1 of the machine. A collar 38, having on it a projection 39, is 15 fastened by a screw 40 to the rod 37, and on the rod 37, between the collar 38 and the part 41 of the base, is a coiled spring 42 which presses upward against the collar, and on the rod 37 above the top plate 3 is a collar 20 43 which is fast on the rod. The stop bar 35 has cut in it on opposite sides slots or recesses 44 at letter space distances apart, and on this bar are tabulator-stops 45 which fit in these recesses and which are adjustable on 25 the bar, each tabulator-stop being formed to engage a recess at the back of the bar and another at the front of the bar. Each tabulator-stop has a lug 46 which extends forward and upward to the body of the stop, 30 secured to the stop bar, when the bar is in its normal position (Fig. 2), in which it is ordinarily held by the upward pressure of the spring 42 against the collar 38 on the rod 37. A stop 47, which is rigidly attached to the 35 back of the carriage 10 about midway between the ends of the carriage, extends backward nearly to the stop bar 35, its rear end being out of alinement with the lugs 46 of the tabulator stops when the stop bar is in its 40 normal position, and then being movable by the carriage past the stops 45 and under the lugs 46.

The rod 37 is pivoted at its lower end to a lever 48 whose fulcrum is a screw 49 passed 45 through its front end and into a boss 50 formed on the frame of the machine. On this lever is an upwardly extending ear 51 in which is a slot 52. A key lever 53, having on it a tabulator-key 54, is pivoted at its rear 50 end by a screw 55 to a lug 56 formed on the underside of the roof 41 of the base and extending downward therefrom, there being behind this lug a coiled-spring 57 bearing against the key lever and the part 41 of the 55 base and tending to keep the key lever in its normal position in contact with a pad 58 near its front end. A pin 59, fixed in the key lever 53, extends through the slot 52 in the ear 51 of the lever 48. The construction is such 60 that when the key 54 is depressed the rear end of the lever 48 is forced downward and the link 37 rocks the stop bar 35, bringing the lugs 46 of the tabulator stops into the path of the stop 47.

65 A lever having arms 60—61 is pivoted by

a shouldered screw 62 to a lug 63 on the underside of the top plate 3, and on the screw 62 is a coiled spring 64 which bears at one of its ends against the lug 63 and at its other end against the lower edge of the arm 60 of 70 the lever, this arm of the lever extending in front of the rod 37 and under the projection 39 of the collar 38, and having on its upper edge a stop 65 which makes contact with the underside of the top plate when the lever is 75 in its normal position, where the spring 64 tends to keep it. A lever substantially the same as this has been used in the Monarch machine to actuate a rack lifting device, operative to raise the carriage rack out of engagement with the escapement pinion, and thus release the carriage from the control of the escapement. Since, however, a part of the carriage-retarding mechanism herein shown is operative through the lever 60—61 80 85 to lift the carriage rack from the pinion 23, the particular lifting device heretofore employed is not necessary in a machine provided with this carriage-retarding apparatus.

The retarding apparatus proper comprises 90 a case containing a mass of particles of solid matter, preferably small chilled shot, and a rotary device contained in the case and arranged to be rotated by the carriage and to act on the mass of matter within the case. 95 The retarding apparatus is preferably constructed and arranged as it is shown herein, although it is apparent that a modification thereof might be adopted. The case, 66, is a hollow cylinder closed at one end by a head 100 67 and at the other end by a screw or plug 68, which fits in and extends across the case and forms the other head of the case. On this screw is a notched disk or flange 69, and on the exterior of the case is a detent in the 105 form of a spring 70, which is fastened to the case by screws 71 and which engages with the notched disk 69, fitting in the notches of the disk as shown in Figs. 4, 5 and 6 and preventing the head or plug 68 from turning. This 110 case is attached by its head 67 to a barrel 72, having on it shoulders or bosses 73 which fit between upright posts of a bracket 74, and the barrel 72 is pivoted on a horizontal axis to these posts 75 by shouldered screws 76 115 120 which extend through the posts into the bosses 73. On the front end of the base of this bracket 74 are lugs 77 which extend upward behind the guide rail 6, and this bracket is attached to the top plate of the machine by a screw 78, the lugs 77 being in contact with the rear face of the guide rail 6. On the front side and near the right end of the barrel 72 is a curved arm 79 on which is formed a tubular bearing 80, the barrel 72, arm 79 125 and the bearing 80 being made in one piece which may be a casting or a drop-forging. The barrel 72 contains a shaft 81 which extends through it from end to end. On the right end of this shaft is a gear 82 which is 130

fast thereon and whose hub is in contact with the right end of the barrel. A shaft 83 extends through the tubular bearing 80 and on the rear end of this shaft, which is horizontal, 5 is a beveled gear 84 which engages with the gear 82, and on the front end of the shaft 83 is a pinion 85, similar to the pinion 23. The rotary device comprises a hub 86 which is fixed on the shaft 81 within the case 66 and 10 from which extend arms 87 which are fast on the hub 86. These arms are preferably round and arranged in pairs at different distances from either end of the hub, the arms extending radially from the hub, as appears 15 by Figs. 6 and 8. A mass of small shot 88 is represented inside of the case.

A lifting device 89 extends through the top plate 3 and is pivoted at its lower end to the arm 61 of the lever 60—61. In the upper part of this lifting device is a slot 90 through which extends the shaft of the pinion 23, the edges of the slot 90 being close to the shaft and the lifting device extending between the pinion 23 and the front end of the 25 bracket 24. At the left of the slot 90 is an arm 91 forming part of the lifting device, and in this arm is a slot 92 through which the shaft 83 passes, the arm 91 extending between the pinion 85 and the front end of the 30 tubular bearing 80. In the base of the bracket 74 is a notch 93, and to the underside of the barrel 72 a spring 94 is attached by a screw 95. This spring extends into the 35 notch 93 and bears against the base of the bracket, tending to hold the barrel 72 and the parts mounted thereon in the positions in which they are shown in Fig. 1, the pinion 85 then being directly under and out of engagement with the rack 20.

40 The machine contains a spring drum 96 which is connected by a strap 97 with a stud 98 affixed to the carriage, so that when the escapement is actuated or the carriage rack is raised out of engagement with the pinion 23, the carriage will be drawn toward the left by the action on it of the spring drum and strap.

The mass of shot 88 within the case 66 should be slightly compressed so that the 50 shot will afford the desired resistance to the rotary device. The shot may be so compressed by turning the head or screw plug 68. This plug may be turned with the fingers when the spring detent 70 has been forced 55 out of engagement with the notched disk or flange 69 of the screw plug.

When the tabulator key 54 is depressed the stop bar 35 is turned on its axis by the action of the lever 53 on the lever 58, and of the 60 latter lever and the rod 37 on the crank arm 36, the lugs 46 on the tabulator stops 45 being moved downward into the path of the stop 47 on the carriage. At the same time the projection 39 on the collar 38, fixed to the 65 rod 37, forces downward the arm 60 of the

ever 60—61, and the lifting device 89 is raised by the arm 61 of this lever, so that the barrel 72 and the parts mounted thereon are turned on the pivotal axis of the barrel to the positions in which they are shown in Fig. 70 5. The carriage rack 20 then engages the pinion 85, and is out of engagement with the escapement pinion 23, from which it has been raised by the action of the other pinion on the rack. The rod 37 is drawn downward 75 until the collar 43 meets the top plate 3, and while this collar is held by pressure on the tabulator key in contact with the top plate, the lugs 46 on the stops 45 are kept in the path of the stop 47, and the barrel 72 and 80 the parts mounted thereon and the carriage rack are kept in the positions shown in Fig. 5. As soon as the rack 20 is thus disengaged from the escapement pinion the carriage is drawn toward the left by the spring drum 96, 85 and the pinion 85, shaft 83, beveled gears 84 and 82, shaft 81 and the rotary device contained in the case 66 are turned together by the action of the rack on the pinion 85. The carriage continues to travel and to so actuate 90 the rotary device until the stop 47 meets the lug 46 on one of the tabulator stops 45. Then the tabulator key is released, whereupon the key and stop bar are restored to their normal positions by the springs 57 and 42, and as 95 the collar 38 on the rod 37 rises, the springs 64 and 94 restore the lever 60—61, the lifting device 89, and the barrel 72 with the parts mounted thereon to their normal positions, the pinion 85 being drawn downward to the 100 position shown in Fig. 1, and the carriage rack descends to the escapement pinion 23 with which it reengages just before the tabulator-stop leaves the stop 47.

When the rotary device 86—87 is actuated 105 as described the arms 87 are forced through the mass of shot within the case 66, portions of the mass being displaced by each arm as the device rotates, and the re-action of the shot on the rotary device tends to reduce the 110 speed of the carriage. The effect of this re-action may be increased or diminished by adjusting the head 68 of the case so as to subject the mass of shot to greater or less pressure.

Obviously other matter might be substituted for the shot shown herein, but the best result has been obtained when a mass of very small chilled shot has been used.

115 By means of the apparatus described the 120 carriage may be retarded, whatever distance it may travel free from the control of the escapement mechanism, as to prevent the machine from being damaged and to render the shock and noise slight when the carriage is 125 arrested by tabulator stops or other similar devices. This retarding apparatus is so constructed and its parts are so arranged, it will be seen, that none of its parts extends as far backward as does the top plate 3 of the 130

machine, so that the apparatus is out of the way and located where it is not in much danger of being damaged.

To adapt the apparatus for use on a machine having a long carriage it is merely necessary to substitute for the beveled gear 84 a larger gear, and for the beveled gear 82 a smaller gear, so as to cause the rotary device to turn at a higher speed when it is actuated by the carriage. All the parts of the apparatus, therefore, with the exception of the beveled gears are applicable to machines having long carriages as well as those having short carriages.

15 It is to be understood that the invention may be applied to machines containing denominational or decimal tabulating mechanism, instead of the particular tabulating mechanism shown herein, or other forms of 20 column selecting mechanism.

Certain combinations disclosed in this application are claimed broadly in my earlier application Serial No. 310,374, filed April 6, 1906, all the claims of this application being 25 limited to combinations not shown in said earlier application.

What I claim as new and desire to secure by Letters Patent, is:—

1. In a typewriting machine, the combination with the carriage of carriage-retarding apparatus arranged to be connected with the carriage, said apparatus comprising a case, a compressible mass of solid matter confined in the case, and a rotary device operative on 35 said matter, said apparatus including means independent of the rotary device for compressing said mass of matter.

2. In a typewriting machine, the combination with the carriage of carriage-retarding 40 apparatus arranged to be connected with the carriage, said apparatus comprising a case, a mass of small incoherent particles of solid matter confined in the case, and a rotary device operative on said matter, said apparatus 45 including means independent of the rotary device for compressing said mass of matter.

3. In a typewriting machine, the combination with the carriage of carriage-retarding apparatus arranged to be connected with the 50 carriage, said apparatus comprising a case, a mass of shot confined in the case, and a rotary device operative on said shot, said apparatus including means independent of the rotary device for compressing said mass of shot.

55 4. In a typewriting machine, the combination with the carriage of carriage retarding apparatus arranged to be connected with the carriage, said apparatus comprising a case a part of which is movable inward and outward, a compressible mass of solid matter confined in the case between said movable part and the opposite wall of the case, and a rotary device operative on said mass of matter.

5. In a typewriting machine, the combination with the carriage of carriage-retarding apparatus arranged to be connected with the carriage, said apparatus comprising a case a part of which is movable inward and outward, a mass of small incoherent particles of solid matter confined in the case between 70 said movable part and the opposite wall of the case, and a rotary device operative on said mass of matter.

6. In a typewriting machine, the combination with the carriage of carriage-retarding apparatus arranged to be connected with the carriage, said apparatus comprising a case a part of which is movable inward and outward, a mass of shot confined in the case between 80 said movable part and the opposite wall of the case, and a rotary device operative on said mass of shot.

7. In a typewriting machine, the combination with the carriage of carriage-retarding apparatus arranged to be connected with the carriage, said apparatus comprising a case a part of which is a screw having at its inner 85 end a surface extending across the case, a compressible mass of solid matter confined in the case between said screw and the opposite wall of the case, and a rotary device operative on said mass of matter.

8. In a typewriting machine, the combination with the carriage of carriage-retarding 95 apparatus arranged to be connected with the carriage, said apparatus comprising a case a part of which is a screw having at its inner end a surface extending across the case, a mass of small incoherent particles of solid 100 matter confined in the case between said screw and the opposite wall of the case, and a rotary device operative on said mass of matter.

9. In a typewriting machine, the combination with the carriage of carriage-retarding 105 apparatus arranged to be connected with the carriage, said apparatus comprising a case a part of which is a screw having at its inner end a surface extending across the case, a mass of shot confined in the case between 110 said screw and the opposite wall of the case, and a rotary device operative on said mass of shot.

10. In a typewriting machine, the combination with the carriage of carriage-retarding 115 apparatus arranged to be connected with the carriage, said apparatus comprising a case a part of which is a screw having at its inner end a surface extending across the case, said screw having on it a notched disk, a detent 120 on the case arranged to engage with said disk, a compressible mass of solid matter confined in the case between said screw and the opposite wall of the case, and a rotary device operative on said mass of matter.

11. In a typewriting machine, the combination with the carriage of carriage-retarding apparatus arranged to be connected with the 125

- carriage, said apparatus comprising a case a part of which is a screw having at its inner end a surface extending across the case, said screw having on it a notched disk, a spring on 65
5 the case arranged to engage with said disk, a compressible mass of solid matter confined in the case between said screw and the opposite wall of the case, and a rotary device operative on said mass of matter.
- 10 12. In a typewriting machine, the combination with the carriage of carriage-retarding apparatus arranged to be connected with the carriage, said apparatus comprising a case a part of which is a screw having at its inner 70
15 end a surface extending across the case, said screw having on it a notched disk, a detent on the case arranged to engage with said disk, a mass of shot confined in the case between said screw and the opposite wall of the 75
20 case, and a rotary device operative on said mass of shot.
13. In a typewriting machine, the combination with the carriage of carriage-retarding apparatus arranged to be connected with the carriage, said apparatus comprising a case a part of which is a screw having at its inner 80
25 end a surface extending across the case, said screw having on it a notched disk, a spring on the case arranged to engage with said disk, a mass of shot confined in the case, and a rotary device operative on said mass of shot.
- 25 30 14. In a typewriting machine, the combination with the carriage of carriage-retarding apparatus arranged to be connected with the carriage, said apparatus comprising a case a part of which is a screw having at its inner end a surface extending across the case, said screw having on it a notched disk, a spring on the case arranged to engage with said disk, a mass of shot confined in the case between 85
35 said screw and the opposite wall of the case, and a rotary device operative on said mass of shot.
- 35 40 15. In a typewriting machine, the combination with the carriage of carriage-retarding apparatus arranged to be connected with the carriage, said apparatus comprising a case, one head of the case being a screw, a compressible mass of solid matter confined in the case, and a rotary device operative on said mass of matter.
- 45 50 16. In a typewriting machine, the combination with the carriage of carriage-retarding apparatus arranged to be connected with the carriage, said apparatus comprising a case, one head of the case being a screw, a mass of shot confined in the case, and a rotary device operative on said mass of shot.
- 55 60 17. In a typewriting machine, the combination with the carriage of carriage-retarding apparatus arranged to be connected with the carriage, said apparatus comprising a case, one head of the case being a screw having on it a notched disk, a detent on the case arranged to engage with said disk, a compressible mass of solid matter confined in the case, and a rotary device operative on said mass of matter.
- 65 70 18. In a typewriting machine, the combination with the carriage of carriage-retarding apparatus arranged to be connected with the carriage, said apparatus comprising a case, one head of the case being a screw having on it a notched disk, a detent on the case arranged to engage with said disk, a mass of shot confined in the case, and a rotary device operative on said mass of shot.
- 75 80 19. In a typewriting machine, the combination with the carriage of carriage-retarding apparatus arranged to be connected with the carriage, said apparatus comprising a case, one head of the case being a screw having on it a notched disk, a spring on the case arranged to engage with said disk, a mass of shot confined in the case, and a rotary device operative on said mass of shot.
- 85 90 20. In a typewriting machine, the combination with the carriage of carriage-retarding apparatus arranged to be connected with the carriage, said apparatus comprising a case a part of which is a screw having at its inner end a surface extending across the case, means to prevent said screw from turning, a compressible mass of solid matter confined in the case between said screw and the opposite wall of the case, and a rotary device operative on said mass of matter.
- 95 100 21. In a typewriting machine, the combination with the carriage of carriage-retarding apparatus arranged to be connected with the carriage, said apparatus comprising a case a part of which is a screw having at its inner end a surface extending across the case, means to prevent said screw from turning, a mass of shot confined in the case between 105
105 said screw and the opposite wall of the case, and a rotary device operative on said mass of shot.
- 110 115 22. In a typewriting machine, the combination with the carriage of carriage-retarding apparatus arranged to be connected with the carriage, said apparatus comprising a case, one head of the case being a screw, means to prevent said head from turning, a compressible mass of solid matter confined in the case, and a rotary device operative on said mass of matter.
- 120 125 23. In a typewriting machine, the combination with the carriage of carriage-retarding apparatus arranged to be connected with the carriage, said apparatus comprising a case, one head of the case being a screw, means to prevent said head from turning, a mass of shot confined in the case, and a rotary device operative on said mass of shot.
24. In a typewriting machine, the combination with the carriage of carriage-retarding apparatus and means including a finger-key

operative to connect said apparatus with the carriage, said apparatus comprising a case, a mass of solid matter confined in the case and normally subjected to pressure therein, and 5 a rotary device including arms which extend into said mass of matter.

25. In a typewriting machine, the combination with the carriage of carriage-retarding apparatus and means including a finger-key 10 operative to connect said apparatus with the carriage, said apparatus comprising a case, a mass of small particles of solid matter confined in the case, and a rotary device including arms which extend into and are 15 rounded by said mass of matter, the thickness of the mass on all sides of each arm being greater than the diameter of any of said particles.

26. In a typewriting machine, the combination with the carriage of carriage-retarding 20 apparatus and means including a finger-key operative to connect said apparatus with the carriage, said apparatus comprising a case, a mass of small particles of solid matter 25 confined in the case, and a rotary device including round arms extending into and surrounded by said mass of matter, the thickness of each arm being less than the thickness of said matter between one side of the arm and the 30 case.

27. In a typewriting machine, the combination with the carriage of carriage-retarding apparatus and means including a finger-key operative to connect said apparatus with the 35 carriage, said apparatus comprising a case, a mass of small particles of solid matter confined in the case and normally subjected to pressure therein, and a rotary device including arms extending into said mass of matter 40 and close to the surrounding wall of said case.

28. In a typewriting machine, the combination with the carriage of carriage-retarding apparatus and means including a finger-key 45 operative to connect said apparatus with the carriage, said apparatus comprising a case having a round body and heads, the inner surface of the body being imperforate and having a regular curvature, a mass of small 50 particles of solid matter confined in the case and extending from one head of the case to the other, and a rotary device including a shaft and means fast thereon, the arms extending into and being surrounded by said 55 mass of matter.

29. In a typewriting machine, the combination with the carriage of carriage-retarding apparatus and means including a finger-key operative to connect said apparatus with the 60 carriage, said apparatus comprising a case, a mass of shot confined in the case, and a rotary device including arms which extend into said mass of shot, the shot being in contact with each arm on all sides thereof.

65 30. In a typewriting machine, the combi-

nation with the carriage of carriage-retarding apparatus and means including a finger-key operative to connect said apparatus with the carriage, said apparatus comprising a case, a mass of shot confined in the case and normally subjected to pressure therein, and a rotary device including arms extending into said mass of shot.

70 31. In a typewriting machine, the combination with the carriage, of carriage-retarding apparatus and means including a finger-key operative to connect said apparatus with the carriage, said apparatus comprising a case, a mass of shot confined in the case, and a rotary device including round arms extending into said mass of shot, the shot being 75 in contact with each arm on all sides of the axis of the arm.

32. In a typewriting machine, the combination with the carriage of carriage-retarding 80 apparatus arranged to be connected with the carriage, said apparatus comprising a case, a mass of small particles of solid matter confined in the case, and a rotary device operative on said matter, said rotary device including arms which are movable through said mass of matter, and said apparatus including means for compressing said mass of matter.

85 33. In a typewriting machine, the combination with the carriage of carriage-retarding apparatus arranged to be connected with the carriage, said apparatus comprising a case, a mass of small particles of solid matter confined in the case, and a rotary device operative on said matter, said rotary device including a hub and arms extending therefrom, said arms being movable through said mass of matter, and said apparatus including means for compressing said mass of matter.

90 34. In a typewriting machine, the combination with the carriage of carriage-retarding apparatus arranged to be connected with the carriage, said apparatus comprising a case, a mass of small particles of solid matter confined in the case, and a rotary device operative on said matter, said rotary device including a hub, and round arms extending therefrom, said arms being movable through said mass of matter, and said apparatus including means for compressing said mass of matter.

95 35. In a typewriting machine, the combination with the carriage of carriage-retarding apparatus arranged to be connected with the carriage, said apparatus comprising a case, a mass of shot confined in the case, and a rotary device operative on said shot, said rotary device including arms which are movable through said mass of shot, and said apparatus including means for compressing said mass of shot.

100 36. In a typewriting machine, the combination with the carriage of carriage-retarding apparatus arranged to be connected with the carriage, said apparatus comprising a case, a

mass of shot confined in the case, and a rotary device operative on said shot, said rotary device including a hub and arms extending therefrom, said arms being movable through 5 said mass of shot, and said apparatus including means for compressing said mass of shot.

37. In a typewriting machine, the combination with the carriage of carriage-retarding apparatus arranged to be connected with the 10 carriage, said apparatus comprising a case, a mass of shot confined in the case, and a rotary device operative on said shot, said rotary device including a hub and round arms extending therefrom, said arms being movable 15 through said mass of shot and said apparatus including means for compressing said mass of shot.

38. In a typewriting machine, the combination with the carriage of carriage-retarding 20 apparatus arranged to be connected with the carriage, said apparatus comprising a case, one head of the case being a screw having on it a notched disk, a detent on the case arranged to engage with said disk, a mass of 25 shot confined in the case, and a rotary device operative on said mass of shot, said rotary device including arms which are movable through said mass of shot.

39. In a typewriting machine, the combination 30 with the carriage of carriage-retarding apparatus arranged to be connected with the carriage, said apparatus comprising a case, one head of the case being a screw having on it a notched disk, a detent on the case arranged to engage with said disk, a mass of 35 shot confined in the case, and a rotary device operative on said mass of shot, said rotary device including a hub and arms extending therefrom, said arms being movable through 40 said mass of shot.

40. In a typewriting machine, the combination with the carriage of carriage-retarding apparatus arranged to be connected with the carriage, said apparatus comprising a case, 45 one head of the case being a screw having on it a notched disk, a detent on the case arranged to engage with said disk, a mass of shot confined in the case, and a rotary device operative on said mass of shot, said rotary 50 device including a hub and round arms extending therefrom, said arms being movable through said mass of shot.

41. In a typewriting machine, the combination 55 with the carriage of carriage-retarding apparatus and means including a finger-key operative to connect said apparatus with the carriage, said apparatus comprising a case, a mass of matter confined in the case, and a rotary device including arms arranged 60 at different distances from the ends of said device and extending into said mass of matter.

42. In a typewriting machine, the combination 65 with the carriage of carriage-retarding apparatus and means including a finger-

key operative to connect said apparatus with the carriage, said apparatus comprising a case, a mass of matter confined in the case, and a rotary device including pairs of arms arranged at different distances from the ends 70 of said device and extending into said mass of matter.

43. In a typewriting machine, the combination with the carriage of carriage-retarding apparatus and means including a finger-key 75 operative to connect said apparatus with the carriage, said apparatus comprising a case, a mass of shot confined in the case, and a rotary device including arms arranged at different distances from the ends of said device and extending into said mass of shot.

44. In a typewriting machine, the combination with the carriage of carriage-retarding apparatus and means including a finger-key 80 operative to connect said apparatus with the carriage, said apparatus comprising a case, a mass of shot confined in the case, and a rotary device including pairs of arms arranged at different distances from the ends of said device and extending into said mass of shot.

45. In a typewriting machine, the combination with the carriage of carriage-retarding apparatus and means including a finger-key 85 operative to connect said apparatus with the carriage, said apparatus comprising a case, a mass of shot confined in the case, and a rotary device including round arms arranged at different distances from the ends of said device and extending into said mass of 90 shot.

46. In a typewriting machine, the combination with the carriage of carriage-retarding apparatus and means including a finger-key 105 operative to connect said apparatus with the carriage, said apparatus comprising a case, a mass of shot confined in the case, and a rotary device including pairs of round arms arranged at different distances from the ends of said device and extending into said mass of 110 shot.

47. In a typewriting machine, the combination with the carriage of carriage-retarding apparatus arranged to be connected with the carriage, said apparatus comprising 115 a case, a mass of matter confined in the case, and a rotary device operative on said matter, said rotary device including arms arranged along its axis, and said apparatus including means for compressing said mass of matter. 120

48. In a typewriting machine, the combination with the carriage of carriage-retarding apparatus arranged to be connected with the carriage, said apparatus comprising 125 a case, a mass of matter confined in the case, and a rotary device operative on said matter, said rotary device including pairs of arms arranged along its axis, and said apparatus including means for compressing said mass of matter. 130

49. In a typewriting machine, the combination with the carriage of carriage-retarding apparatus arranged to be connected with the carriage, said apparatus comprising 5 a case, a mass of shot confined in the case, and a rotary device operative on said shot, said rotary device including arms arranged along its axis, and said apparatus including means for compressing said mass of shot.
- 10 50. In a typewriting machine, the combination with the carriage of carriage-retarding apparatus arranged to be connected with the carriage, said apparatus comprising 15 a case, a mass of shot confined in the case, and a rotary device operative on said shot, said rotary device including pairs of arms arranged along its axis, and said apparatus including means for compressing said mass of shot.
- 15 51. In a typewriting machine, the combination with the carriage of carriage-retarding apparatus comprising a rotary device, two beveled gears engaged with each other, and a pinion, the axis of rotation of 25 the rotary device and one of said beveled gears being in a vertical plane parallel to the axis of the platen, and the axis of rotation of the other beveled gear and said pinion being horizontal, and said pinion being movable 30 into and out of engagement with the carriage-rack.
52. In a typewriting machine, the combination with the carriage of carriage-retarding apparatus comprising a shaft whose 35 axis of rotation is in a vertical plane parallel to the axis of the platen, a rotary device fast on said shaft, a beveled gear fast on said shaft, a horizontal shaft, a beveled gear fast on said horizontal shaft and engaged with 40 the other beveled gear, and a pinion fast on said horizontal shaft, said shafts being mounted in bearings permanently secured together and movable on a horizontal axis to engage said pinion with and disengage it 45 from the carriage rack.
53. In a typewriting machine, the combination with the carriage of carriage-re-
- tarding apparatus comprising a shaft whose axis of rotation is in a vertical plane parallel to the axis of the platen, a rotary device fast 50 on said shaft, a beveled gear fast on said shaft, a horizontal shaft, a beveled gear fast on said horizontal shaft and engaged with the other beveled gear, a pinion fast on said horizontal shaft, a barrel forming a bearing 55 for the first mentioned shaft, said barrel being mounted on a fixed axis, a bearing for the horizontal shaft formed on said barrel, and means for turning said barrel on its pivotal axis to engage said pinion with and disengage it from the carriage rack.
54. In a typewriting machine, the combination with the carriage and carriage-feed mechanism of carriage-retarding apparatus comprising a horizontal shaft movable upward and downward, a pinion fast on said shaft, and a vertically movable lifting device having in it slots through which said shaft and the shaft of the escapement pinion extend, the last mentioned shaft forming a 70 guide for the lifting device and said horizontal shaft being movable by the lifting device to engage the pinion on the horizontal shaft with and disengage it from the carriage rack.
55. In a typewriting machine, the combination with the carriage and carriage-feed mechanism of carriage-retarding apparatus comprising a horizontal shaft movable upward and downward, a pinion on said shaft, and a vertically movable lifting device having in it slots through which said shaft and the shaft of the escapement pinion extend, each of said slots being open at its outer end and the lateral edges of the slot containing 80 the last mentioned shaft extending up and 85 down and those of the other slot extending towards the sides of the machine.

Signed at Syracuse, in the county of Onondaga and State of New York, this 9th day of July, A. D. 1906.

HERBERT H. STEELE.
